(57) **CLAIM**

The ornamental design for a housing for utility sensors, as shown and described.

DESCRIPTION

FIG. 1 is a top, rear perspective view for a housing for utility sensors showing my new design;

FIG. 2 is a left side sectional view cut through section 2-2 of front view 5.

FIG. 3 is a right side view thereof;

FIG. 4 is a left side view thereof;

FIG. 5 is a front view thereof;

FIG. 6 is a rear view thereof;

FIG. 7 is a top view thereof;

FIG. 8 is a bottom view thereof; and,

FIG. 9 is a top front perspective view thereof shown in an environment of use.

The broken line showing of a utility transformer and a utility power pole are included for the purpose of illustrating the environment of the claimed design and form no part thereof. The interior of the housing for utility sensors shown with broken oblique lines in FIG. 2 forms no part of the claimed design.
